Inventor:

United States Patent Office.

DANIEL H. TURNER, OF NEW YORK, N. Y.

Letters Patent No. 77,935, dated May 12, 1868.

IMPROVED APPARATUS FOR COOLING AND PURIFYING BONE-BLACK.

The Schedule referred to in these Letters Patent and making part of the same.

TO ALL WHOM IT MAY CONCERN:

Be it known that I, DANIEL H. TURNER, of the city, county, and State of New York, have invented a new and useful Improvement in Apparatus for Cooling and Purifying Animal Charcoal, of which the following is a full, clear, and exact description, reference being had to the accompanying drawing forming part of this specification, and in which—

Figure 1 represents a longitudinal sectional elevation of an apparatus constructed according to my improvement, and

Figure 2 a transverse section of the same.

Similar letters of reference indicate corresponding parts in both figures.

This, my improvement, has reference to that description of apparatus for cooling and purifying animal charcoal, or, as it is otherwise termed, revivifying bone-black, in which the coal is operated upon in a comparatively close and compact manner, but without exposure of it in dense quantities, and the gases, dust, and other impurities effectually removed by agitating or giving the coal a series of successive lifts as it is passed along a revolving vessel or hollow body, through which a current of cool air is made to pass.

In this connection my present improvement differs from the apparatus shown and described in Letters Patent of the United States, (No. 68,915,) issued to me, September 17, 1867, in substituting for a revolving reticulated horizontal cylinder, provided with spiral lifters for passage of the coal, a combination of horizontal close cylinder, so provided, and screen-extension thereto, together with a hot-air, gas, and dust conductor at the back end of the cylinder, and to which may be attached a Hancock or other blower, as in the apparatus patented to T. H. Quick, on May 15, 1866, and November 26, 1867; and said invention further consists in a combination, with such an arrangement, of a distributing-apron, within the conductor, for the purpose of distributing the hot coal in the cooling and purifying-cylinder; also, the invention includes a sliding or adjustable device to the close cylinder and screen-extension, for the purpose of regulating the extent of screening-surface, to increase or diminish the delivery of coarser and valuable dust circumferentially, while the cold and clean coal is discharged through the open front end of the cylinder or its screen-extension.

Referring to the accompanying drawing, A represents a cylinder, set horizontally, or thereabouts, on a revolving shaft, B, to which it is secured, and through means of which it is driven by any suitable power. Said cylinder A is of an open character at its ends, but of a close construction, circumferentially, excepting at or near its forward end, where it is made to connect with or to form a screen-extension, C, the forward end of which lies over a coal-delivery spout or chute, D, attached, say, to the frame E, which carries the apparatus.

F is the hot-air, gas, and dust conductor, arranged at the opposite or back end of the cylinder A, and which may be connected by a suitable extension, G, with a Hancock, steam, or other blower. Within this conductor is arranged a distributing-apron, H, that serves to convey and distribute the reburnt coal from a feed-spout, I, into the cooling-cylinder A, which, in revolving, passes the hot coal along it, and, by means of internal lifting-strips J, to said cylinder, and which are preferably of a spiral character, causes it to be subjected to a succession of lifts, the coal falling back repeatedly as each strip approaches its uppermost position, and, whilst thus agitated and opened or distributed, said coal is exposed to a natural or forced draught of cold-air, which enters at the open or front end of the cylinder A, or its screen-extension C, and is made to pass through the coal, and in an opposite direction to the advancing course of it, carrying off all impurities, including fine dust and heated gases, up through the conductor F, the cooled and clean coal escaping at the opposite end down the chute D. This is essentially different to my previously-patented arrangement of a horizontal revolving screen, hereinbefore referred to, and has a superior action upon the coal to a vertical arrangement of cylinder. But, by combining the screen-extension C with the close cylinder A, at its forward end, I am enabled to sift the coal, prior to delivery from the machine, of all or most of its coarser and valuable dust not passing off with the current, and which may be regulated, as regards proportion or amount thus sifted, by means of a sliding ring or cover, K, adjustable along the cylinder A, and over the screen C, circumstances sometimes requiring more of such dust to be collected separately from the clean coal, and at other times less.

The arrangement of the distributing-apron H within the conductor, effectually secures the proper distribution of the hot coal within the cooling-cylinder.

What is here claimed, and desired to be secured by Letters Patent, is—

1. The combination of the circumferentially close revolving cylinder A, provided with interior lifters, and set horizontally, or thereabouts, with the screen, or screen-extension C, at the forward end of said cylinder, and hot-air, gas, and dust conductor F, for operation together substantially as specified.
2. In combination with the circumferentially close cylinder A, and screen forward extension C, the adjustable ring or cover K, essentially as shown and described.
3. The arrangement, within the conductor F, of the distributing-apron H, for operation in connection with the cylinder A, provided with lifters, and set horizontally, or thereabouts, as herein set forth.

D. H. TURNER.
